HERBERT W. CHENEY, OF MILWAUKEE, WISCONSIN, ASSIGNOR TO ALLIS-CHALMERS COMPANY, OF MILWAUKEE, WISCONSIN, A CORPORATION OF NEW JERSEY.

ENGINEER'S VALVE.

1,030,229.

Specification of Letters Patent. Patented June 18, 1912.

Application filed October 20, 1911. Serial No. 655,691.

To all whom it may concern:

Be it known that I, HERBERT W. CHENEY, a citizen of the United States, residing at Milwaukee, in the county of Milwaukee and 5 State of Wisconsin, have invented a certain new and useful Improvement in Engineers' Valves, of which the following is a specification.

This invention relates to improvements in 10 the construction of engineer's valves for use in controlling air brake systems of railway cars.

The object of the invention is to provide 15 an engineer's valve in which the valve and valve stem are automatically returned to lap or mid-position, so that if the operating handle is removed from the stem while the valve is in any other position than lap 20 position, that is, in brake set or brake release position, the valve will be automatically returned to lap position.

A clear conception of one embodiment of 25 the invention can be had by referring to the accompanying drawing forming a part of this specification, in which like reference characters designate the same or similar parts in the different views.

Figure 1 is a central vertical section 30 through a rotary engineer's valve having a means for returning the valve to lap or mid-position, applied thereto. Fig. 2 is a section through the valve and valve stem, the section being taken on the line II-II of Fig. 1, looking downward.

The engineer's valve consists essentially 35 of a valve casing or cap 2, a valve stem 3, valve body 12, valve seat 13, and valve seat support or base 14. The operating handle 1 coacts with the upper end of the valve stem 40 3, thereby permitting rotation of the stem and through it the valve 12. The handle 1 may be removed from the stem 3 with the valve 12 in any position. An oil pan 4 is formed in one with the stem 3 within the 45 cap 2. A transverse key 11 is formed in one with the lower portion of the stem 3 and is adapted to coact in a slot formed in the upper portion of the valve 12. The valve 12 is adapted to control a series of ports 15, 50 16, passing through the valve seat 13 and valve seat support or base 14.

The helical spring 5 is coiled around the portion 9 of the stem 3 between the oil pan 4 and the key 11. The spring 5 has out-

wardly projecting ends 8, 18, which coact 55 against opposite sides of the lug 7 and central stop or rib 6. The lug 7 is formed in one with the key 11 and can be removed from the stem 3 with the removal of the key 11 by withdrawing the screw 10. The rib 60 6 projects radially inward from the cap 2, being formed in one with the cap 2.

During the operation of the valve, the 65 stem 3 is given an oscillatory movement to either side of the central or lap position, in which position the valve is disclosed in the drawing, thereby rotating the valve 12 by means of the key 11 to form a connection between various ports to either release or set the brakes, as desired. Suppose the valve 70 12 to be rotated through the medium of the stem and handle 1 in an anti-clockwise direction. The end 8 of the spring 5 will then retain its coaction with the rib 6, while its contact with the lug 7 will be broken. The 75 end 18 of the spring 5 will break its contact with the rib 6 and will maintain its coaction with the lug 7. The rotation of the stem will cause the spring 5 to be wound more tightly around the portion 9 of the 80 stem, thereby compressing the spring 5. Upon releasing the turning pressure applied to the handle 1, the spring 5 will immediately return the stem 3 and hence the valve 12 to the position shown in Fig. 2. 85

By turning the valve 12 in a clockwise direction, the end 18 of the spring 5 will retain its coaction with the rib 6 only, while the end 8 will retain its coaction with the lug 7 only. Upon releasing the turning 90 pressure, the stem 3 will again be returned to lap position.

It will be seen from this construction, that if the handle 1 is removed from the valve and the stem should by any means be turned 95 to any position other than lap, a release of the turning power will immediately cause the valve 12 to return to lap position. The use of a spring as shown, is merely one disclosure of the invention, but it is not desired 100 to be limited to this construction as other means, such as fluid pressure or gravity, might be utilized for returning the valve.

It should be understood that it is not desired to be limited to the exact details of 105 construction shown and described, for obvious modifications will occur to a person skilled in the art.

It is claimed and desired to secure by Letters Patent,—

1. In an engineer's valve, a casing, a valve within said casing, means for operating said valve, and a spring having end portions directly engaging a portion of the inner wall of said casing and adapted to return said valve to normal from any other position.
- 10 2. In an engineer's valve, a casing, a valve within said casing, means for operating said valve, a single stop on said casing, and a spring having ends directly engaging opposite sides of said stop and adapted to 15 return said valve to normal from any other position.
- 15 3. In an engineer's valve, a casing, a valve within said casing, a stem for operating said valve, means for operating said stem, and a

spring for automatically returning said 20 valve and stem to normal from any other position, said spring surrounding said stem and having end portions directly engaging a portion of the inner wall of said casing.

4. In an engineer's valve, a casing, a valve 25 within said casing, means for operating said valve, a stop on said casing, and a helical spring having end portions directly engaging said stop, the engagement between said spring ends and stop being such that movement of said valve away from normal position will cause said spring to coil up.

In testimony whereof, I hereto affix my signature in the presence of two witnesses.

HERBERT W. CHENEY.
